J. R. HAAS

FLOUR SIFTER

Filed April 5, 1923

INVENTOR:

Jacob R. Haas,

BY: Oliver O. Martin,

HIS ATTORNEY.

UNITED STATES PATENT OFFICE.

JACOB R. HAAS, OF CHICAGO, ILLINOIS.

FLOUR SIFTER.

Application filed April 5, 1923. Serial No. 630,013.

To all whom it may concern:

Be it known that I, JACOB R. HAAS, a subject of the King of Yugoslavia, and resident of Chicago, in the county of Cook and State of Illinois, have invented new and useful Improvements in Flour Sifters, of which the following is a specification.

This invention has relation to improvements in flour sifters, such as used in the average household, and it pertains particularly to means rendering such sifting device suitable for storing flour, thereby enabling the householder to keep the device on the pantry shelf and to use it from day to day, without danger of spilling flour on shelf or floor.

To this end my object is to provide, in a device of the character mentioned, a pivotally hung bottom, which normally maintains the sifter device closed so tightly that no flour will be spilled. A further object is the provision of convenient operating means, whereby the bottom may be turned on its pivot entirely out of the way of the falling flour, during the sifting operation. Another object is to lock the bottom in withdrawn position during the sifting operation. A further object is the provision of improved means for rotating the agitator within the sifter. Another object is to combine the various features just enumerated for simultaneous operation, by the one hand holding the device, leaving the other hand entirely free for other purposes.

With the foregoing objects in view my invention consists in the various combinations hereinafter described and claimed; and a drawing is hereto annexed, illustrating the application of my device to a flour sifter.

In the drawing:

Fig. 1 is a side elevation, partly in section of a flour sifter embodying the invention.

Fig. 2 illustrates the device as viewed from the rear, and parts are broken away in order to disclose the enclosed operating mechanism of my device.

The sifter comprises a cylindrical shell 1, into which is set a substantially semi-spherical screen 2, above which is placed a pivotally mounted agitator 3. Rigidly mounted on the shell 1 is a tubular handle 4, within which practically all the operating mechanism of the device is placed. An operating rod 5 projects above the handle, and

this rod is provided with a toothed side edge 55 meshing with a gear pinion 7 of the agitator pivot 8. A depression of the rod 5, which for this purpose is fitted with a fingerpiece 10, causes the pinion 7, and with it the agitator 3, to revolve. A suitable spring 11 60 serves to restore the rod to its initial position. It is readily seen by those versed in the art, that a series of depressions of the rod 5, by the thumb of the hand holding the device, imparts a continuation of revolutions 65 to the agitator. The person performing this operation may simultaneously be stirring the substance, into which the sifted flour falls, with the other hand, thereby affording a great improvement over the old style sifters, 70 in which both hands are employed, one to hold the sifter and the other to turn the agitator.

Below the rod 5, and in continued alignment therewith, is a bar 12, and this bar is 75 provided on one edge with gear teeth 13, which in turn mesh with the teeth of a pinion 14. The latter rotates on or with a pivot 15, and it carries with it a pair of arms 16, which arms are rigidly mounted on the flange 17 of a bottom disc 18. A suitable spring 19 serves to maintain the parts last mentioned in their normal, elevated position, wherein the bar 12 abuts the bottom end of the rod 5. In view of the foregoing it is 80 readily understood that a depression of the rod 5 causes the bar 12 to move downward, and to turn the sifter bottom on its pivot. The parts are properly proportioned to swing the bottom entirely out of the way, 85 substantially as indicated in dotted outline in Fig. 1. Adjacent to the bar 12 is hung a pawl 20, which by gravity or by a suitable spring 21 is urged into engagement with a notch 22 of the bar, when the latter is fully 90 depressed, thereby maintaining the sifter bottom open. The person operating the device can now pump the agitator rod as long as required, without danger of closing the bottom. It is true, of course, that the rod, 95 at the end of its stroke may strike the end of the bar 12, but the operator soon becomes cognizant of this condition and learns not to depress the rod quite so far. In other words, the initial stroke should be complete, 100 and the succeeding pump strokes a trifle shorter. A slight pressure on the heel 23 of the pawl 20 suffices to disengage the pawl 105

from the notch in the bar, whereupon the bottom of the sifter instantly is drawn closed by its spring.

It may be suggested that the spring 11 will have to be quite powerful in order to rotate the agitator while restoring the rod 5, and that, for this reason the pressure required on the fingerpiece 10 will be so great as to make the device hard to operate. That, of course, will entirely depend upon the size, or rather diameter of the screen and agitator. But this difficulty may also be overcome by introducing a ratchet mechanism, substantially as shown. In order to employ such ratchet mechanism it is necessary that the pinion 7 be loosened so as to turn freely on the pivot 8. Rigid on the end of this pivot is then mounted an arm 24 carrying a spring-held pawl 25, and the latter rides in the teeth of the pinion. A depression of the rod 5 results in a rotation of the pinion against the direction of and carrying with it the pawl 25, the arm 24 and the agitator 3. As the latter again rises it is seen that the pawl 25 clicks idly over the gear teeth. In other words, the agitator is then given an intermittent movement in the same direction.

As the device of my invention is intended for use as a combined and self contained flour can and flour sifter it is, of course, well to provide a cover on the shell 1. Such cover, 26, is shown in the drawing pivotally hung at 27, but whether hinged or entirely detachable, it should be made fairly tight, so that no dust or moisture will get into the can. The flange 17, on the hinged bottom 18, is also quite important, as it prevents spilling of what little flour may be shaken through the screen, when the device is not in operation as a sifter.

I wish it clearly understood that the structure shown in the drawing is merely pictorial, and that I reserve right to modify the parts and movements sufficiently to produce a marketable device. It is also to be understood that only sufficient is shown to indicate the construction of my device, and that the mechanic will be required to provide guides for the sliding rod and bar, and to perform such additional operations as usually come within the scope of his activities.

I claim:—

1. In a normally closed flour sifter provided with a handle rigidly affixed, a screen, an agitator, means operable by the hand gripping the handle to rotate said agitator, and means actuated by said rotating means to open the bottom of the device.
2. In a normally closed flour container, means for holding the container with one hand, and co-operating means for rotating said agitator and opening the bottom of the container with the same hand.
3. In a flour container comprising, a shell,

a handle rigid on the shell, and a normally closed bottom, means projecting from said handle and operable by the hand clutching the handle, to open said bottom, and means maintaining said bottom opened.

4. A flour container comprising a shell having a rigidly affixed tubular handle, a screen within the shell, an agitator for said screen, means enclosed within said handle and operable by the hand gripping the handle to rotate said agitator.

5. In a flour container supportable by one hand, a screen, an agitator, a normally closed bottom, and means engageable by the thumb of the hand supporting the container simultaneously to operate said agitator and open the said bottom.

6. In a flour container having a tubular handle, a sifter device, and sifter operating means within the handle, said means having a projecting fingerpiece operable by the hand gripping the handle.

7. In a flour container, a cylindrical shell, a tubular handle on said shell, a hinged bottom normally closed, an operating rod vertically movable within said handle and connected to swing the bottom upon its hinge, said rod depressible by the hand engaging the handle, and manually releasable means maintaining the bottom open.

8. In a flour container, a cylindrical shell, a tubular handle rigid on the shell, a hinged bottom normally closed, an operating rod vertically movable within said handle, an agitator pivotally hung within the shell, one of the pivots extending into said handle, a pinion on said pivot, said pinion engaged by said rod to rotate the agitator, means actuated by said rod to open the bottom, and a fingerpiece on said rod, said fingerpiece operable by the hand engaging the handle to rotate the agitator.

9. In a flour container and sifter, a handle, a hinged bottom normally closed, means operable by the hand engaging the handle to swing the bottom open, and manually releasable means maintaining the bottom open during the sifting operation.

10. In a flour container and sifter, a handle, a hinged bottom normally closed, a pinion on the pivot of said bottom, and means engaging said pinion to swing the bottom open on its pivot, said means operable by the hand engaging the handle.

11. In a flour container and sifter, an agitator, means for rotating said agitator, a hinged bottom normally closed, means actuated by said agitator rotating means to swing said bottom open, means maintaining the bottom open during the sifting operation, and means releasing the bottom for automatic closing.

12. In a flour container and sifter, a shell, a handle on said shell, a hinged bottom having a flange encompassing the lower end of

the shell, means operable to swing the bottom open, means maintaining the bottom open, and means releasing the bottom for automatic closing.

- 5 13. In a flour container and sifter, a shell, a handle on the shell, an agitator within the shell, a rod vertically movable within said handle, said rod on its downstroke connected to rotate said agitator, and resilient means urging the return of the rod independently of said agitator.

14. In a flour container and sifter, a shell, a handle on said shell, a hinged bottom having a flange encompassing the lower extremity of the shell, means within the handle for swinging the bottom open, and means for maintaining the bottom open during the sifting operation. 15

In testimony whereof, I have hereunto affixed my signature.

JACOB R. HAAS.
